United States Patent Office

Des. 180,562
Patented July 2, 1957

180,562

SWIM SUIT

Frank Mansueto, Chicago, Ill.

Application February 23, 1956, Serial No. 40,296

Term of patent 14 years

(Cl. D3—17)

Fig. 1 is a front view of a swim suit showing my new design, and

Fig. 2 is a rear view thereof.

The swim suit is illustrated as worn by a female figure shown in dotted lines in the drawing.

I claim:

The ornamental design for a swim suit, as shown and described.
